UNITED STATES PATENT OFFICE.

WILHELM SIMMCHEN, OF AUSSIG-KLEISCHE-ON-THE-ELBE, CZECHOSLOVAKIA.

LETTING-OFF MECHANISM FOR LOOMS.

Application filed August 27, 1921. Serial No. 495,956.

To all whom it may concern:

Be it known that I, WILHELM SIMMCHEN, a citizen of the Czechoslovak Republic, residing at Aussig - Kleische - on - the - Elbe, 5 Czechoslovakia, have invented certain new and useful Improvements in Letting-Off Mechanism for Looms, of which the following is a specification.

This invention relates to letting-off mechanism for looms, having means for automatically regulating the delivery of the warp from the warp-beam in accordance with the decreasing diameter of the warp on the beam and for maintaining the warp at a uniform 10 tension.

It has been proposed to use for this purpose a weighted feeler lever, which moves as the diameter of the warp decreases, and thereby shifts a stud in a slotted link or lever, so that the effective leverage producing the let-off motion is increased. In this connection means have been provided permitting adjustment of the let-off motion be effected according to the density of weft 20 required, one of the levers having a slot or a series of holes at which another lever or actuating member can be connected to it at varying distances from its fulcrum to regulate the rate of feed.

30 In the structure embodying my invention I also use these elements, but for regulating the rate of feed, and consequently the density of the weft, I provide means for a two-fold adjustment, namely means for adjusting the connection of the lay or other driving member to the primary actuating lever of the feed motion mechanism, and means for adjusting the connection of an intermediate lever comprised in the feed motion mechanism to the gear which imparts rotation to the warp beam. I thus combine in the mechanism two features which, while not novel separately, have in combination with each other the novel and valuable effect of enabling a coarse preliminary adjustment for weft density, to be followed by a very accurate precise adjustment, the whole adjustment extending over a very wide range.

40 In addition I provide a spring brake, acting on the feed gear, for example on a ratchet wheel forming part of that gear, to assist in maintaining the warp at uniform tension and being so adjusted that it will yield in case of excessive pull.

45 I may so arrange and combine the several elements that they can be mounted conven-

iently on a single frame piece or bracket, which can be bolted or otherwise fixed to the frame of practically any current type of loom.

50 In order to regulate the throw of the ratchet and thereby the motion imparted to the warp beam, in accordance with the diminishing diameter of the beam, I associate with the warp beam a feeler responding to 55 the change of diameter and connect this feeler to part of the lever coupling mechanism so that the leverage is regulated as required.

The invention is illustrated in the annexed 60 drawings, showing a construction particularly adapted for the Hodgsen loom.

Fig. 1 is a side elevation of the mechanism.

Fig. 2 an elevation of the holder whereby 65 the mechanism is fixed to the frame of the loom.

Fig. 3 a vertical section of the ratchet gear and brake on the line U—V Fig. 1 and

Fig. 4 a section thereof on the line X—Y 70 of Fig. 1.

The actuating rod *a* whereof a portion is shown in Fig. 1, is connected to the lay and to a stud *b*, which is adjustable in a longitudinal slot *c* provided in a lever *d*. A stud *e* fixed to the lever *d* forms a pivot for a link *f*, having at its opposite end a stud *g*, which engages in a slot *g*¹ provided in a double-armed lever *h* pivoted at 14 in a bracket 12 mounted on the loom frame and carrying 80 the entire letting-off mechanism. The upper arm of the lever *h* has a series of holes 1, 2, 3, into either of which can be inserted a stud carried at one end of a link *i*, said link being connected at its other end to a lever *l* 85 having a plurality of pawls *m* at its upper end. These pawls *m* engage a ratchet wheel *n* and by virtue of their different lengths, as shown in Fig. 3, a very slight movement of link *i* will cause one of the pawls to engage 90 and impart rotation to the ratchet wheel. This rotation is transmitted by the train of gear wheels *o*, *p*, *q*, *r* to a shaft *s*, and thence by gear wheels *t* and *u* to the warp beam *v* 95 journalled at *w*.

A feeler lever 4 pivoted on a shaft 5 carries on an arm 41 a weight 6 whereby a roller 40 journalled at the end of the feeler is held against the warp coiled on the beam. A spring may be used instead of the weight 6 100 as an equivalent means.

The feeler is provided with another arm 7

connected by a link 8 to the stud *g* already referred to, so that movement of the feeler about its pivot 5 causes the stud *g* to slide one way or the other in the slot *g*¹ and to thus alter the throw of the pawls *m*. Broken lines in Fig. 1 represent the positions of the feeler roller 40 when the circumference of the warp on the beam is at its maximum and minimum respectively; the feeler 4 is shown 10 in this figure in full lines in an intermediate position, with the warp beam *v* about half full, as indicated by a broken line circle portion.

As the circumference of the warp beam 15 decreases, the stud *g* is moved upwards towards the pivot 14 of the lever *h* and the throw of the pawls *m* is thus increased. When the diameter of the warp beam has been reduced by half, the throw of the pawls *m* and thus the rate of rotation of the beam 20 is doubled, so that the circumferential velocity of the beam remains the same and thus the let-off remains the same as when the weaving started with a full beam.

25 Coarse preliminary regulation of the rate of feed, for roughly determining the weft density, is made by selecting the hole 1, or 2, or 3 for coupling the link *i* to the lever *h*, this being an operation roughly corresponding to what has heretofore frequently been effected by changing gear wheels, the present operation being much simpler and speedier. Fine adjustment of the weft density is then made by setting the stud *b* 30 in the slot *c*. Adjustment of the feed within very wide limits is thus possible. A range of from 9 wefts to 92 wefts per centimeter, for example, can be accomplished without difficulty. In Fig. 2, 10 designates part of 40 the frame of the loom, and 11 a bracket bolted thereto, supporting a casting 12 having bearings for shafts 13 and 14, on which the levers *d* 1 and *h* are mounted, and also for the pivotal shaft 5.

45 Upon a squared portion 20 of the shaft 13 is mounted a U-shaped brake member 15 provided with leather brake-shoes 21 held against the web of the ratchet wheel *n* by the action of a spring 16 bearing against the member 15. The pressure exerted by this spring is adjustable by means of nuts 22 screwed on to the threaded end of the shaft. This brake normally puts a drag on the ratchet wheel *n* after the same has been 50 rotated by the pawl; when for each weft in turn a definite predetermined let-off has taken place, but under certain circumstances the brake would yield to allow the cloth beam to draw yarn off the warp beam, as for example where the yarn is badly warped so that "soft" places occur on the warp beam.

60 The mechanism can be modified in detail in many ways without departing from the general principle set forth.

What I claim as my invention, and desire to secure by Letters Patent of the United States of America is:

1. Letting-off mechanism for looms comprising in combination a warp beam, a ratchet feed wheel and an actuating lever therefor carrying the pawl for said wheel, a train of gears, whereby said feed gear rotates the warp beam, a spring controlled brake acting on said feed gear and comprising a spring actuated U-shaped member frictionally bearing against said ratchet wheel, a vibratory primary actuating lever having a slot for finely adjustably connecting it with a suitable driving member of the loom, 70 a second intermediary slotted vibratory lever, coarsely adjustable means for connecting said second lever to the feed gear actuating lever, a feeler lever in contact with the warp on the warp beam and movable in accordance with the amount of warp on the beam and means controlled by said feeler lever adjustably connecting the primary actuating lever with said second lever for the purpose of controlling the delivery 80 speed of the warp beam in accordance with the decreasing diameter of the warp thereon, to maintain the warp at a uniform tension and to permit a coarse and a fine preliminary adjustment of said ratchet gear 85 for adjusting the weft density.

2. Letting-off mechanism for looms comprising in combination a warp beam, a ratchet feed wheel and an actuating lever therefor carrying the pawl for said wheel, a train of gears, whereby said feed gear rotates the warp beam, a spring controlled brake acting on said feed gear and comprising a spring actuated U-shaped member frictionally bearing against said ratchet wheel, 100 a vibratory primary actuating lever having a slot for finely adjustably connecting it with a suitable driving member of the loom, a second intermediary slotted vibratory lever, coarsely adjustable means for connecting said second lever to the feed gear actuating lever, a feeler lever in contact with the warp on the warp beam and movable in accordance with the amount of warp on the beam and means controlled by said feeler lever adjustably connecting the primary actuating lever with said second lever for the purpose of controlling the delivery speed 105 of the warp beam in accordance with the decreasing diameter of the warp thereon, to maintain the warp at a uniform tension and to permit a coarse and a fine preliminary adjustment of said ratchet gear for adjusting the weft density, 110 said primary lever being pivotally mounted on the pivotal axle 115 of said ratchet lever.

3. Letting-off mechanism for looms comprising in combination a warp beam, a ratchet feed wheel and an actuating lever therefor carrying the pawl for said wheel, a 120

train of gears, whereby said feed gear rotates the warp beam, a spring controlled brake acting on said feed gear and comprising a spring actuated U-shaped member 5 frictionally bearing against said ratchet wheel, a vibratory primary actuating lever having a slot for finely adjustably connecting it with a suitable driving member of the loom, a second intermediary slotted vibratory lever, coarsely adjustable means for connecting said second lever to the feed gear actuating lever, a feeler lever in contact with the warp on the warp beam and movable in accordance with the amount of warp 10 on the beam and means controlled by said feeler lever adjustably connecting the primary actuating lever with said second lever 15

for the purpose of controlling the delivery speed of the warp beam in accordance with the decreasing diameter of the warp thereon, to maintain the warp at a uniform tension and to permit a coarse and a fine preliminary adjusting of said ratchet gear for adjusting the weft density, all of said levers and said feed gear being mounted on a single frame attachable to the frame of the loom. 20 25

In testimony whereof I affix my signature in presence of two witnesses.

WILHELM SIMMCHEN.
